Primary Examiner — Abraham Bahta(74) *Attorney, Agent, or Firm* — Quarles & Brady LLP; James J. Aquilina**CLAIM**

The ornamental design for a lighting device, as shown and described.

DESCRIPTION

FIG. 1 is a front perspective view of a lighting device showing our new design;

FIG. 2 is a front view thereof;

FIG. 3 is a left side view thereof, the right side view being a mirror image thereof;

FIG. 4 is a top view thereof; and,

FIG. 5 is bottom view thereof.

The broken lines in FIGS. 1–5 show unclaimed portions of the lighting device. The rear view is omitted and forms no part of the claimed design. The oblique line shading in FIGS. 1, 2, and 5 shows translucent or transparent materials.
